UNITED STATES PATENT OFFICE

LEE B. SEE, OF CUMBERLAND, MARYLAND

CAR REPLACER

Application filed May 2, 1928. Serial No. 274,562.

This invention relates to car replacers and one object of the invention is to provide a device of this character which may be temporarily disposed adjacent one side of a rail 5 and the wheels of a car which has become derailed easily guided back into proper position upon the rails of a track.

Another object of the invention is to so form the car replacer that, when in position 10 for use, it may be very firmly held in place and prevented from accidentally being moved longitudinally of a rail or away from the same transversely thereof.

Another object of the invention is to provide 15 a device of this character which may be placed either in front of or behind the wheels of a derailed car and guide the wheels onto the rails.

Another object of the invention is to so 20 form the car replacer that it will be very strong but at the same time comparatively light in weight and also to permit water to pass through its intermediate portion and thereby prevent it from being subjected to 25 pressure which might move it out of its proper position if a track is flooded and a stream of water is flowing across the track.

Another object of the invention is to so 30 proportion the car replacer that, when in place, it will not prevent the wheels of a car upon the track from moving along the track past the replacer and also to prevent danger of the replacer being tilted away from a rail out of an upright position when in use.

35 The invention is illustrated in the accompanying drawing, wherein—

Figure 1 is a top plan view showing the replacer in operative relation to a portion of a track;

40 Fig. 2 is a view showing the replacer in side elevation and the ties of a track upon which it rests in section;

Fig. 3 is a transverse sectional view taken on the line 3—3 of Fig. 2, and

45 Fig. 4 is a perspective view of the replacer and a portion of the track.

The replacer, which is indicated in general by the numeral 1, is formed of metal having sufficient strength to support the weight of 50 a car without danger of its breaking and is

preferably of such length that when in use it will extend across three of the ties 2 which support the rails 3 of a track with its ends resting upon two of the ties and its intermediate portion supported upon a tie, as 55 shown in Figs. 2 and 4.

By an inspection of Fig. 2, it will be seen that the body portion of the replacer is formed with a flat under face which extends in an even plane throughout its length and 60 also in an even plane throughout its width, as shown in Fig. 3, so that it has a wide bearing surface which rests upon the upper faces of the ties. This body is relatively wide and when in place occupies practically the entire 65 distance from the outer edge of the base of a rail to the outer ends of the ties, and therefore, it will be well supported and when in use there will be no danger of the pressure 70 exerted by the weight of a car causing the replacer to tilt out of an operative position. Spurs 4 and 5 extend downwardly from the intermediate and end portions of the body adjacent opposite sides thereof and bite into the ties, as shown in Figs. 2 and 3, so that the 75 replacer will be firmly anchored to the ties and prevented from moving out of its proper position relative to a rail. It should be noted that the spurs 5 extend downwardly at an inward incline so that they will very effectively 80 serve to prevent the replacer from being forced longitudinally of the track when it is in use.

The body portion of the replacer increases 85 in thickness from its ends towards its intermediate portion thereby providing the replacer with an upper surface having its end portions 6 sloping upwardly from its ends towards its intermediate portion 7 which is disposed in a horizontal plane substantially 90 parallel to the under face of the body. Grooves 8 extend longitudinally of the replacer in the upper surface thereof and have their outer ends opening through the ends of the body and their inner end portions 95 extending across the flat intermediate portion 7 of the upper surface of the body. It should be noted that the inner end portions of these grooves are curved outwardly and disposed in crossed and intersecting 100

relation to each other and open through the side edge faces of the body. Therefore, when the flange of a car wheel is engaged in one of the grooves and moved longitudinally therein, it will be guided towards a side of the body as it approaches the intermediate portion thereof and may pass out of the groove onto the rail of the track. It should be further noted that the grooves decrease in depth from the ends of the body towards the inner ends of the grooves and that the intermediate portion of the body is of such thickness that when the replacer is in use its intermediate portion will be of approximately the same depth as the depth of a rail of a standard construction. This is clearly shown in Fig. 3 and referring to this figure it will be seen that, when the wheel reaches the inner end of a groove, it will be in proper position to move easily upon the tread face of the head of a rail and at such an elevation that it can easily ride onto the rail. Recesses 9 are formed at the sides of the under face of the body and are of such depth that when the replacer is in use a portion of the base of a rail may be snugly received in one of the recesses and thereby retain the replacer parallel to the rail with the intermediate portion of its side edge face in flat contacting engagement with a side face of the head of a rail. Since the grooves 8 lead from both ends of the body, the replacer may be set in place either in front of or in back of a wheel of a car to be replaced and since grooves are formed adjacent each side edge of the body the replacer may be used at either side of a track with equal facility and no special care must be exercised when setting it in place. It should be further noted that when the device is in use the groove which receives the flange of a wheel is close to the rail and the replacer for the greater portion of its width projects outwardly from the wheel towards the end of a tie. Therefore, the replacer will be very firmly supported and there will be no danger of the pressure exerted by the weight of a car causing it to tilt out of an operative position.

In order to reduce the weight of the replacer and permit it to be easily handled, there has been provided an opening or passage 10 which extends the full width of the body and is of greater length than the flat intermediate portion 7 of the upper surface of the body. This opening or passage is reduced in depth towards its ends thereby providing the passage with upper and lower walls 11 and 12, the upper one of which is in the form of an arch and, therefore, will be very strong and not liable to easily break when subjected to heavy pressure. This opening or passage not only reduces the weight of the replacer so that it can be easily carried but also permits it to be readily grasped when it is to be lifted and in addition provides a passage through which water may flow if the track is flooded

and a stream of rapidly flowing water is moving transversely across the track. This permits the replacer to be easily moved towards a rail into proper position for use after it has been set upon the end portions of the ties to support it. Recesses 13 are formed in the edge faces of the replacer so that it may be easily grasped when it is to be moved longitudinally of the ties into proper engagement with a rail or it is desired to slide the replacer along the ground out of the way when it is not in use and temporarily placed upon the ground and openings 14 are formed in the wall 12 so that the replacer may be suspended upon pins projecting from a working car and thereby suspended out of the way but in such position that it can be easily reached when needed.

Having thus described the invention, I claim:

1. A car replacer comprising an elongated body increased in thickness from its ends towards its intermediate portion and having its intermediate portion of an even thickness to provide the upper surface of the body with a flat intermediate portion and sloping end portions, the said upper surface of the body having longitudinally extending grooves formed therein gradually sloping towards the sides of the body from its ends and having their inner end portions curved outwardly across the flat intermediate portion of the upper surface of the body in crossed relation to each other and opening through a side edge face of the body.

2. A car replacer comprising an elongated body increased in thickness from its ends towards its intermediate portion and having its intermediate portion of an even thickness to provide the upper surface of the body with a flat intermediate portion and sloping end portions, the said upper surface of the body having longitudinally extending grooves formed therein gradually sloping towards the sides of the body from its ends and having their inner end portions curved outwardly across the flat intermediate portion of the upper surface of the body in crossed relation to each other and opening through a side edge face of the body, the intermediate portion of the body being of a thickness approximately corresponding to the height of a rail along one side of which the replacer is to be disposed when in use and the grooves gradually decreasing in depth from the ends of the body to their inner ends.

3. A car replacer comprising an elongated body increased in thickness from its ends towards its intermediate portion and having its intermediate portion of an even thickness to provide the upper surface of the body with a flat intermediate portion and sloping end portions, the body being relatively wide and adjacent one side having its upper surface formed with longitudinally extending

grooves leading from its ends and having their inner end portions curved outwardly across the flat intermediate portion of the upper surface in crossed and intersecting relation to each other and opening through the adjacent side edge face of the body.

4. A car replacer comprising an elongated body increased in thickness from its ends towards its intermediate portion and having its intermediate portion of an even thickness to provide the upper surface of the body with a flat intermediate portion and sloping end portions, the said upper surface of the body having longitudinally extending grooves formed therein gradually sloping towards the sides of the body from its ends and having their inner end portions curved outwardly across the flat intermediate portion of the upper surface of the body in crossed relation to each other and opening through a side edge face of the body, the intermediate portion of the body being of a thickness approximately corresponding to the height of a rail along one side of which the replacer is to be disposed when in use and the under face of the body having a recess along its intersection with the said side edge face to receive the side edge portion of the base of a rail.

5. A car replacer comprising an elongated body increased in thickness from its ends towards its intermediate portion and having its intermediate portion formed with spaced upper and lower walls and open at its sides between the walls to provide an opening through the intermediate portion of the body, the upper face of the body having grooves formed longitudinally therein and leading from the ends of the body with their inner end portions curved outwardly across the intermediate portion of the body in crossed and intersecting relation to each other and opening through the adjacent side edge face of the body.

6. A car replacer comprising an elongated body increased in thickness from its ends towards its intermediate portion and having its intermediate portion formed with spaced upper and lower walls and open at its sides between the walls to provide an opening through the intermediate portion of the body, the upper face of the body having grooves formed longitudinally therein and leading from the ends of the body with their inner end portions curved outwardly across the intermediate portion of the body in crossed and intersecting relation to each other and opening through the adjacent side edge face of the body, the lower wall of the intermediate portion of the body having openings formed therein whereby the replacer may be suspended from supporting pins when not in use and the side edges of the body having finger-receiving recesses formed therein adjacent opposite ends of the opening in its intermediate portion.

7. A car replacer comprising an elongated body increased in thickness from its ends towards its intermediate portion and having its intermediate portion formed with spaced upper and lower walls and open at its sides between the walls to provide an opening through the intermediate portion of the body, the upper face of the body having grooves formed longitudinally therein and leading from the ends of the body with their inner end portions curved outwardly across the intermediate portion of the body in crossed and intersecting relation to each other and opening through the adjacent side edge face of the body, and anchoring prongs extending downwardly from the under face of the body adjacent its ends and intermediate its length and adapted to be embedded in ties to retain the replacer in a set position, the end prongs extending downwardly at an inward incline to prevent longitudinal movement of the replacer.

In testimony whereof I affix my signature.
